SHEET FEEDING APPARATUS

Robert Currie, Eastport, Maine, assignor to
American Can Company, New York, N. Y., a corporation of New Jersey

Application February 15, 1932, Serial No. 592,941

14 Claims. (Cl. 271—27)

The present invention relates to a sheet feeding apparatus and has particular reference to the automatic removal of single sheets from a stack of sheets, the removal of each sheet being in timed sequence with the disposal of a previously separated sheet.

The principal object of the present invention is the provision of an apparatus for successively separating single sheets from a stack of sheets 10 within a magazine and feeding each sheet in a step by step movement for a series of operations, the feeding of each successive sheet being automatically determined by the completion of operations upon a preceding sheet.

15 An important object of the invention is the provision of an automatic control for a sheet feeding apparatus which actuates separating devices to remove a sheet from a stack of sheets within a magazine only after a previously separated sheet has passed beyond a predetermined position.

An important object of the invention is the provision of a sheet feeding apparatus of the character described which embodies sheet separator 25 and sheet feeding devices by means of which a separated sheet is fed downwardly through a series of predetermined distances and through controlling elements which insure further sheet separation so that one sheet will follow another 30 in processional order without interruption of the operations of the apparatus.

A further important object of the invention is the provision of cutting or shearing mechanism 35 for successive operation upon a sheet after it has been automatically removed from a magazine and while it is being fed in a step by step movement, the trim remaining after the last cut on the sheet being automatically discharged from the apparatus.

40 Numerous other objects of the invention will be apparent as it is better understood from the following description, which, taken in connection with the accompanying drawings, discloses a preferred embodiment thereof.

45 Referring to the drawings:

Figure 1 is a side elevation of a sheet feeding apparatus embodying the present invention;

Fig. 2 is a plan sectional view taken substantially along the line 2—2 in Fig. 1;

Fig. 3 is an enlarged longitudinal sectional view taken through the separating devices substantially along the line 3—3 in Fig. 4;

Fig. 4 is a transverse sectional view taken substantially along the line 4—4 in Fig. 2;

Fig. 5 is a sectional detail taken substantially along the line 5—5 in Fig. 3;

Fig. 6 is a view similar to Fig. 5 illustrating a different position of the parts;

Fig. 7 is an enlarged detail of a part of the sheet separating device;

Fig. 8 is a front elevation, partly in section, of the parts illustrated in Fig. 7, as viewed along the broken line 8—8 in that figure;

Fig. 9 is a sectional detail taken substantially along the line 9—9 in Fig. 7;

Fig. 10 is a view similar to Fig. 4, showing some of the parts in different positions; and

Fig. 11 is an enlarged elevation, partially in section, of a portion of the sheet separating device. 70

The apparatus disclosed in the drawings for the purpose of exemplifying the present invention, comprises a magazine in which a plurality of sheets are placed in stacked position, preferably standing on edge. The front part of the magazine is open and sheets may be placed within to restore the supply of stacked sheets while the feeding apparatus is in operation. The sheets are separated or removed singly from the rear of the magazine, by reciprocating suction cups. 75

The suction cups make one forward and one backward movement and then remain stationary until after a full cycle of operations has been completed. At the end of the forward stroke the suction cups engage the rearmost sheet and as they move back, the engaged sheet is pulled away from its stacked position and brought into a vertical position. 85

This separated sheet is then released by the suction cups and falls into the first of its feeding positions. While still maintained in vertical position the sheet is lowered and advanced a predetermined distance in a step by step movement. During such step movement, it is successively subjected to operating devices of suitable character and an operation takes place upon the sheet at each of its rest periods. 90

Cutting instrumentalities are herein selected for purposes of illustrating such devices and these operate, upon each stroke of a reciprocating slide, 100 to cut a given width of strip from the sheet. After all of the sheet has been cut into strips there remains a trim severed from the upper edge of the sheet and this trim is thereupon automatically ejected from the cutting members.

Controlling devices are provided which intermittently move against the sheet in time with the slide movement and as long as a sufficient amount of the sheet extends in their path of travel. When the upper edge of the sheet has passed 105

110

- below the controlling devices, they actuate a latch or locking element connected with a clutch associated with the suction cups. It is only when the parts are brought into clutched position that the suction cups again move forward and back and a succeeding sheet is then extracted from the magazine and caused to pass through the cycle of movements just described, without interruption of the operations of the apparatus.
- 10 The magazine frame for the stack of sheets comprises a pair of spaced vertically disposed rails 26 (Figs. 1, 2, 4 and 10) secured together at their upper ends by a tie rod 27 and fastened at their lower ends to forwardly extending angle irons 28. There is an angle iron for each rail, the inner ends of each angle iron at its junction with the rail being connected to a bracket 29 by a bolt 31 which extends through the walls of both angle iron and rail.
- 15 Each bracket 29 is secured by a bolt 32 to a horizontal plate 33, the two plates supporting the frame of the magazine. Each plate 33 is also secured by the bolt 32 to a post 34 which rests upon and is supported by a block 35 mounted upon a main casing 36. The two blocks 35 extend beyond the bottom of the magazine frame and support posts 37 which provide spacers for the forward ends of the two plates 33, bolts 38 being used to secure the parts 33, 37 and 35 together. The forward end of each angle iron 28 is secured to and supported by an extension 41 projecting upwardly from the plate 33.
- 20 Side walls 45 are provided for the lower part of the magazine, there being a wall located inside of each of the rails 26. These walls are mounted upon the horizontal legs of the angle irons 28 and are spaced from their vertical legs by spacing blocks 46. A strap 47 is mounted upon the horizontal leg of each angle iron 28 and the two straps together provide a floor for the lower edges of sheets 51 placed in stacked position within the magazine. The sheets are stacked slightly inclined from the vertical and the upper part of the stack rests against and is supported by the tie rod 27. The bottom part of the stack is held within the magazine by side plates 52 which are secured to the rear edges of the bars 26 by bolts 53. Each plate 52 extends inwardly beyond the edge of its bar 26 and the rearmost sheet within the stack rests against the extending parts.
- 25 Projections 55, 56 preferably extend toward the front and rear of each bar 26 adjacent its upper end and these provide side guides for retaining the stack of sheets in position within the magazine. The construction of the magazine as just described leaves the forward part open for the insertion of sheets and this may be done at any time irrespective of the removal of the sheets from the rear of the magazine. In this way a supply of sheets may be maintained in the stack without interrupting the operation of feeding. The sheet separating or suction devices comprise a pair of suction cups 61 (Figs. 2, 3, 4, and 10), each cup being formed with a cylindrical head 62 on which is secured a suction rubber 63, screws 64 being used for this purpose. Each suction cup is extended rearwardly in a tubular stem section 65 which is threadedly connected at 66 with a crossbar 67. This bar is loosely mounted at its ends in arms 68 secured to a rockshaft 69 journaled in bearings 75 formed in the upper ends of vertical brackets 76 secured by bolts 77 to a cross frame 78 mounted upon and secured to the casing 36.
- 30 The arms 68 thus support the bar 67 and fur-

ther means are provided for maintaining the suction cups in the desired horizontal or angular positions throughout their travel. The loose connections between bar 67 and arms 68 permit this supplemental control which includes a cam device best illustrated in Figs. 2, 4 and 10. The bar 67 is formed with an upwardly extending arm 85 which carries a pin 86 on which a cam roller 87 is rotatably mounted. This roller is disposed within a cam groove 88 formed in a cam plate 89 bolted at 91 to a bar 92. The ends of the bar 92 are secured to the brackets 76, bolts 93 passing through spacer sleeves 94 being used for this purpose.

35 The shaft 69 oscillates to effect the forward and back movement of the suction cups when separating and removing a sheet 51 from the magazine and the cam groove 88 of the cam 89 working against the roller 87 rocks the bar 67 in its arm support sufficiently to bring the suction cups squarely into sheet engaging position. The rubbers 63 of the suction cups are thus brought against the rear face of the rear sheet in the stack, the cups being under suction at such time. As the rubbers are withdrawn on the back stroke 100 of the cups, the lower end of the sheet is pulled away from the stack, its center part bending sufficiently to snap its side edges past the retaining plates 52.

40 To effect the necessary suction in the cups 105 for this temporary holding of the sheet as it is pulled away from the stack, air is removed from interior of the cups. Each suction cup head 62 is hollow and encloses a chamber 101 (Fig. 3) which communicates with a passageway 102 110 formed in the stem 65 each passageway being in constant communication with a transverse passageway 103 formed longitudinally of the bar 67. The passageway 103 does not extend throughout all of the length of the bar, and one end is 115 stopped off by a plug 104 threadedly secured in the end of the bar.

45 An air valve is provided for closing and opening communication with the passageway 103. This valve comprises a movable valve member 120 105 (see also Figs. 5 and 6) which is located within an opening 106 transversely cut through the bar 67 substantially at its center. This opening 106 crosses the passageway 103 at substantially right angles and the valve 105 is cut circumferentially in a groove 107 which normally registers with the passageway 103, as shown in Figs. 3 and 5.

50 The valve is spring held in this position, the valve member 105 extending rearwardly of the bar 67 in an enlarged head 108. A compression spring 109 is confined between the head and the rear end of the bar, the spring encircling the body of the valve. A cotter pin 111 is inserted in the forward end of the valve member and 135 provides a stop for holding the groove 107 in proper register with the passageway 103 when the valve member is held by the spring.

55 A nipple 115 is threadedly secured in the bar 67 directly above and in communication with the opening 106 in the bar and provides an attachment for a hose 116 which connects with a suitable source of vacuum such as a vacuum pump or a vacuum tank.

60 Air is drawn in through the open ended cups 145 and carried into the hose 116 when the valve 105 is in its normal position, this air passing through the cup chambers 101 and along the passageway 102, 103, around the groove 107 and through the nipple 115.

When the cup rubbers 63 engage the sheet to be separated the open or front end of each chamber 101 is closed and the air is immediately removed causing a partial vacuum and the sheet then adheres to the cup faces and is withdrawn from the stack with the backward movement of the suction cups.

As the bar 67 reaches the end of its backward stroke, the suction effect in the cups 61 is broken 10 and the separated sheet is released from engagement with the suction rubbers 63. This will now be explained. A stop screw 121 (Figs. 2, 4 and 10) threadedly secured to the bar 92 is held in an adjusted position by a locknut 122 the inner end of 15 the screw being in the path of travel of the valve member 105 as it is carried back with the bar 67. The last end of movement on the backward stroke of the bar brings the head 108 of the valve member 20 into engagement with the stationary screw 25 and the valve member 105 is shifted relative to its opening 106. This is against the action of the spring 109 which is compressed as the bar 67 reaches the end of its travel.

This backward position is determined by the bar 67 striking against stop screws 123 threadedly engaged in the bar 92. Each screw 123 is held in adjusted position by a locknut 124. The suction valve is now in the position illustrated in Figs. 6 and 10, the groove 107 of the valve member being out of alignment with the nipple 115, and the body of the valve member cutting off communication with the vacuum pipe 116.

Not only are the suction cups cut off from vacuum but they are open to atmosphere. A transverse bore 125 extends through the valve member 105 and in the last described position of the valve this bore is in communication with the passageway 103. The bore 125 connects with a longitudinal bore 126 which is further extended laterally 19 in a short bore 127 open to atmosphere, all of these openings being formed in the valve member. Air entering the ports 127, 126, 125 and the passageways 103 and 102 fills the cup chambers 101, thus breaking the vacuum within the suction cup heads 62.

The suction cup rubbers no longer hold the sheet which is in a vertical position (as illustrated in Fig. 10) with its lower outer face against the vertical wall of the cross frame 78. Bars 131 (Figs. 4 and 10) secured by bolts 132 to the bottom side of the magazine extend rearwardly in curved projections 133 which are directly below the lower edge of the sheet 51 during its movement from the magazine and constitute safety guides 55 for the sheet directing the sheet into feeding position.

The upper part of the separated sheet 51 is lightly held against the stack of sheets in the magazine by a pair of spring fingers 134 (see also Fig. 7) secured by screws 135 to the upper ends of the brackets 76. The sheet in its vertical position is now ready for step feeding into any desired operating devices which act successively upon adjacent sections of the sheet during its rest periods.

In the drawings, there is disclosed by way of example, a cutting device for severing the sheet into strips 141 of predetermined width (Figs. 4 and 10). The cutting devices comprise a cutting blade 142 secured by bolts 143 to the underside of the cross frame 78. The forward face of this blade is in alignment with the forward wall of the cross frame and it is alongside of this wall that the separated sheet 51 moves downwardly during its step by step advance through the cutting

mechanism. A second, cooperating blade 145 is secured by bolts 146 to the front end of a slide 147 (see also Fig. 2) which moves back and forth in side grooves 148 formed in the blocks 35. The blade 145, as it is carried inwardly by the slide 147, passes under the cutting blade 142, the inner edges of the two blades overlapping (Fig. 10). The parts are in this position when the sheet is released from the suction cups.

The slide 147 is formed with laterally extending arms 151 (Figs. 1 and 2) which carry pivot pins 152 to which connecting rods 153 are pivotally secured. Each rod 153 is connected at 154 to the upper end of a lever 155 pivoted at 156 to one side of the casing 36. The lever 155 carries at its lower end a pivot pin 157 on which is rotatably mounted a cam roller 158 operating within a cam groove 159 of a face cam 161 secured to a drive shaft 162. The shaft 162 is journaled in bearings 163 formed in the casing 36 and is rotated in any suitable manner as by connection with a drive pulley 164 fixed on one end of the shaft.

The slide 147 carries a pair of spaced, horizontally disposed rods 171 (Figs. 4 and 10) which are beneath the bottom edge of the separated sheet 51 when it drops from the cups 61. It comes to rest on these pins, this initial feeding position being shown in Fig. 10.

Each rod 171 is carried in a tubular housing 172 formed with spaced legs 173 bolted at 174 to the upper surface of the slide 147. Each rod extends longitudinally through its housing and carries a collar 175 adjacent its inner end. The outer end of each rod is threaded for the reception of nuts 176 located exterior of the housing. 110 A spring 177 surrounds each rod 171 and is confined between the collar 175 and the end wall of the housing. This spring allows for shifting of the rod in its housing and normally holds it in inner extended position with the locknuts 176 115 resting against the outer end walls of the housing, as illustrated in Figs. 2 and 4.

When the slide 147 moves out or away from the frame 78 it carries the housings 172 and the enclosed pins 171 back into the position illustrated 120 in Fig. 4, the inner ends of the pins moving out from under the sheet 51 which thereupon again drops down. The sheet this time is assisted in its movement by a feeding device embodying feed rollers 181 (see also Fig. 2) mounted on a horizontal shaft 182.

The shaft 182 is journaled in bearings formed in brackets 183 bolted to the face of the cross frame 78 on opposite sides of the machine. Shaft 182 carries at one end a sprocket 180 and a chain 184 operating over this sprocket also passes over a sprocket 185 carried on the drive shaft 162. The continual rotation of the drive shaft through the described connections imparts similar rotation to the rollers 181 which rub against the sheet 135 and draw it downwardly.

The bottom edge of the sheet is brought into engagement with stop plates 191 secured to the casing 36 on opposite sides of the machine. Each plate 191 is provided with a projection 192 which 140 forms a backing wall for a pocket and holds the sheet in its vertical position for its first cutting operation which immediately follows.

As the slide 147 moves inwardly, its cutting blade 145 is brought against the sheet adjacent 145 its bottom edge and the first strip 141 is sheared from the sheet. The remainder of the sheet now rests upon the cutting member 145. The severed strip 141 is pushed forward by the forward inner edge of the cutting blade 145 and pivoting on its 150

supported lower edge, as illustrated in Fig. 10, falls through an opening 193 in the upper wall of the casing 36.

The slide 147 is withdrawn and the blade 145 moves out from under the remaining part of the sheet. The feeding rollers 181 which have been idly turning against the surface of the sheet during the cutting action now assist in forcing it downwardly until its bottom edge again comes 10 into place upon the stop plates 191. This operation is repeated until the sheet is advanced through a sufficient number of successive cuttings to convert it into its series of strips 141.

Prior to the two final cuts, the suction cups 15 are again actuated to feed another sheet into cutting position so that there will not be any idle cutting stroke, the succeeding sheet following immediately after the sheet before. The timing of the separation of sheets from the magazine takes 20 place automatically and is dependent upon the progress of the preceding sheet through its cutting cycle. In this way sheets of any width (or more correctly height as they rest in the magazine) may be fed through the machine and cut 25 into strips. This automatic actuation will be fully described but attention is first directed to the final cutting operation on each sheet.

To insure uniformity of widths of strips each sheet is a little wider than the aggregate strip 30 widths and a small remainder or trim 201 (Fig. 10) must be removed from the upper edge of the last strip during the final cutting stroke of the slide 147. When this shearing or trim cut is completed and while the cutting members are 35 overlapped the trim 201 is upon the upper surface of the cutting blade 145. From this position it is immediately discharged from the apparatus by a blast of air in the following manner.

As the slide 147 advances for the trim cut, a 40 rod 203 (Figs. 4 and 10) carried thereby trips an air valve located in a compressed air line. This rod is slideably held in horizontal openings formed in the legs 173 of one of the housings 172. A collar 204 is pinned to the rod intermediate the 45 posts 173 and a spring 205 is disposed on the rod and is confined between the collar and one of the posts. This spring normally holds the rod in an extended position (Fig. 4).

During all of the cutting strokes of the slide 50 147 excepting the final trim cut now being considered there is enough left of the sheet to extend above the plane of movement of the rod and accordingly on each forward or inward stroke of the slide the inner end of the rod strikes against 55 the sheet and is held from further movement. It, therefore, slides within its bearings as the slide 147 and its housing 142 moves inwardly its full stroke. This is done against the action of the spring 205 which comes under greater compression.

At the final trim cut the upper edge of the remaining part of the sheet is below the rod 203 and the inner end of the rod passes into a horizontal opening 206 formed in the cross frame 78. The 65 rod engages one end of a sliding pin 207 disposed in the opening and pushes it longitudinally a short distance. The pin 207 is provided with a head 208 which rests against an operating lever 209 of an air valve 211. Valve 211 is disposed in 70 a compressed air line and connects with an air supply pipe 212. The valve at its bottom is connected with a pipe 213 threadedly secured in the cross frame.

The interior of the pipe 213 communicates with 75 a horizontal passage 214 cut in the frame 78 and

its inner end communicates with an inclined passage 215. The end of the passage 215 is at a point directly above the trim 201 as it rests (Fig. 10) upon the cutting blade 145 following the final severing operations upon the sheet. The sliding of the pin 207 by the rod 203 and the resulting opening of the valve 211 permits a blast of air to escape from the opening 215 and it impinges against and under the relatively light trim 201. This bodily lifts the trim piece from its position and blows it through a channel 216 formed in the slide 147, where it falls out of the machine. As soon as the slide 147 moves back a spring confined within the valve 211 restores the lever 209 and rod 207 to normal position (Fig. 4).

The actuation of the suction cups for the feeding of the next sheet depends primarily upon a device actuated by the rods 171 (Figs. 4 and 10). During all of the cutting strokes of the slide 147 excepting the last two cuts, there is enough left 95 of the sheet to extend above the plane of movement of the rods 171. Accordingly, on each active stroke of the slide the inner ends of the rods strike against the sheet and come to rest while the slide and housing 172 complete their inward 100 travel. The springs 177 yield to permit this action. At the next to the last and at the final trim cut, the rods, being unobstructed, move into openings 218 cut through the cross frame 78.

One of the rods strikes against a block 219 105 located in one of the openings and pushes it outwardly a short distance. The block 219 is in engagement with a finger 221 which is shifted at such time. This finger is secured to a rockshaft 222 journaled in a bearing 223 which is clamped 110 against the cross frame 78 and in a bearing 224 formed in one of the brackets 76. The shaft 222 is thus oscillated and moves an arm 226 (see also Figs. 7 and 8) which is pinned on the shaft and which is pivoted at 227 to a bar 228 connecting 115 its opposite end to a pivot 229 carried in a block 231. This block oscillates on a stud 232 projecting outwardly from one side of the bracket 76.

The pin 229 provides a pivotal mounting for a pawl 233 which engages one of eight teeth of a 120 ratchet wheel 234 mounted on the stud and moves it through an arc of approximately 45°. This is effected by the movement, just described, of the block 219 under the action of the rod 171. It will be observed that the relatively slight movement 125 of the finger 221 is compounded by long lever 226 which insures ample movement for the ratchet wheel 234. A stop bolt 241 adjustably carried in a bracket 242 limits the amount of upward movement of the lever 226, a locknut 243 threaded on 130 the bolt holding the latter in adjusted position. Bracket 242 is bolted to the bracket 76.

Since there will be two movements of the slide 147 (the next to the last and the final trim cutting strokes) when the pins 171 pass unobstructed 135 into the openings 218 the block 219 is moved twice for each sheet cycle. The ratchet wheel 234 is accordingly turned two times both in the same direction, that is, clockwise as viewed in Fig. 7. The first movement closes a clutch device which 140 connects the suction cups organization with a constantly swinging part and the second movement of the ratchet wheel opens the clutch and brings the suction cups to rest. This will be better understood by reference to Figs. 7 and 8.

The shaft 69 at one end carries an arm 245 (see also Figs. 1, 2 and 7), which is free to oscillate upon the shaft and which is also pivotally engaged at 246 with a link 247 which connects at 150

its opposite end to a pivot 248 carried on the upper end of an arm 249 secured by bolts 251 to the lever 155. This arm 245 constitutes the constantly swinging part of the clutch device and 5 the arm rocks back and forth upon the shaft 69 simultaneously with each forward and back stroke of the slide 147 with two exceptions. One backward and one forward movement is made by the arm when it does not rock on the shaft. The first 10 is a backward movement accompanied by the return of the slide after the next to the last cutting stroke and the second immediately follows accompanying the forward movement of the slide for its final trim stroke. For those two movements 15 the arm is locked to and moves the shaft together with the suction cups, the clutch device referred to providing the desired connection.

An arm 261 (Figs. 2, 7, 8, 9 and 11) is secured to the shaft 69 adjacent the arm 245 and a collar 20 262 is also pinned to the shaft on the opposite side of the arm. The arm 261 is slotted longitudinally at 263 for the reception of a sliding block 264. This block is inserted into the end of the arm and its outer end is formed as a latching 25 tongue 265 which constitutes one element of the clutch device. Block 264 also carries a pin 266 on which is rotatably mounted a roller 267 which is used for controlling the position of the block relative to the arm 261. A spring 268 is located 30 between the end wall of the groove 263 and the inner end of the block 264 and tends to hold the tongue in projecting or locking position.

The arm 245 is formed with a projection 271, which constitutes the other element of the clutch 35 device, this projection being slotted at 272 for the reception of the tongue 265. When the parts are in clutched position, the spring 268 holds the clutch elements together, as shown in Fig. 11.

The position of the ratchet wheel 234 determines 40 whether the spring 268 will hold the clutch elements locked together or whether the roller 267 will move the block 264 inwardly to establish an unclutched condition. A block 275 is used for this purpose and is mounted on the upper 45 end of a rod 276 vertically disposed in a boss 277 projecting outwardly from the bracket 76 directly above the ratchet wheel. The rod 276 carries a feather 278 which slides within a featherway formed within the boss and prevents 50 turning of the rod but allows for vertical movement in its bearing.

The lower end of the rod 276 carries a roller 55 279 which rides upon a starwheel 281 which may be integral with the ratchet wheel 234. Starwheel and ratchet are preferably united by a connecting sleeve 282 mounted on the stud 232. These parts on the stud 232 are held against uncontrolled movement by a spring 283 located on the outer end of the stud and pressing against 60 the end of the sleeve. A nut 284 threadedly engaged on the outer end of the stud holds the spring under sufficient compression.

The starwheel 281 is formed with four high 65 sections 287 and a corresponding number of intermediate low sections 288. At the time the ratchet wheel 234 begins its first clockwise movement, as previously described, one of the high sections 287 is directly under the roller 279 and the rod 276 and block 275 are in raised position. 70 At such time the arm 261 is in vertical position and the roller 267 on the block 264 is held in raised position, this roller resting upon the top of the block 275. The spring 268 is under compression and the tongue 265 of the clutch device 75 is held up in non-projecting position.

This is the normal unclutched position maintained by these parts during the several oscillations of the arm 245, the shaft 69 with its suction cups remaining in a stationary position.

During the first movement of the ratchet wheel 80 and the starwheel 281 through the first of its 45° of travel, the supporting high section 287 moves beyond the roller 279 and allows it to drop into the adjacent low section 288 (Fig. 7). This movement lowers the rod 276 and the block 275 and the spring 268 thereupon causes the block 264 to follow downwardly, the roller 267 still resting upon the top of the block 275.

The latch or tongue 265 is thus projected outwardly and at the end of the forward stroke of the slide 147, the arm 245 comes into vertical position. Its projection 271 is thus brought directly beneath the end of the arm 261 and its slot 272 is in alignment with the tongue 265. The upper face of the projection on both sides of the slot may be curved as shown so as to slightly lift the tongue, if necessary, during the movement of the slot beneath the tongue. A clutch connection is thus established between the arms 245, 261 and they move forward together, the 95 shaft 69 oscillating in its bearings and the suction cups moving into engagement with the next sheet in the magazine. Separation of the sheet is effected as the suction cups move toward the left (Fig. 1), this being in synchronism with the forward movement of the slide 147 upon its 100 final trimming stroke.

The ratchet wheel 234 and the starwheel 281 move again, this time on their respective second arcs of travel of forty-five degrees and the low 110 part 288 in the starwheel moves beyond the roller 279 as the next adjacent high section 287 moves into position on top. This lifts the rod 276 and the block 275 is again raised. At the same time the arm 261 is bringing the roller 267 against the 115 block 275 and in its vertical position, the roller rests upon the upper surface of the raised block 275. The block 264 now being in raised position the clutch elements are disconnected.

To insure easy disengagement of the tongue 265 from its slot 272 a spring device is used. This device yieldingly opposes the lateral frictional thrust of the tongue against one of the walls of the slot of the clutch which is brought about by the engagement of the roller 267 against the block 120 275 as the suction cups come back into normal 125 position.

The spring device used for this purpose is mounted upon a strap 291 (Figs. 7, 8 and 9) fastened by screws 292 to the side of the arm 245. This strap is bent inwardly at one end where it is 130 formed with a sleeve section 292 which carries a pin 293. The inner end of the pin is in alignment with the arm 261 and as the arm 245 swings back into alignment with the arm 261, the pin engages the edge of the latter. A spring 294 is mounted upon the pin 293 and is confined between the end of the sleeve 292 and a collar 295 secured to the pin.

Locknuts 296 threadedly secured to the outer 140 end of the pin 293 provide a stop for the pin when it is moved inwardly by the spring 294, this being when the arm 245, unclutched, swings away from the arm 261. The engagement between the end of the pin 293 and the arm 261 145 takes place at one end of the oscillation of the arm 245 when the arm 261 and the suction cups remain stationary, such momentary engagement insuring that the bar 67 is brought up against the screws 123.

It is thought that the invention and many of its attendant advantages will be understood from the foregoing description and it will be apparent that various changes may be made in the form, 5 construction and arrangement of the parts without departing from the spirit and scope of the invention or sacrificing all of its material advantages, the form hereinbefore described being merely a preferred embodiment thereof.

10 I claim:

1. A sheet feeding apparatus, comprising in combination, a magazine for holding a plurality of sheets on edge in stack formation, separating devices for removing a single sheet from one side 15 of said magazine, means for releasing the sheet to drop by gravity, and means for feeding said separated sheet downwardly in a step by step movement.

2. A sheet feeding apparatus, comprising in combination, a magazine for holding a plurality of sheets on edge in stack formation, separating devices for removing a single sheet from the rear side of said magazine, means for releasing said sheet to drop edgewise by gravity, means for feeding said separated sheet downwardly in a step by step 25 movement, said feeding means being adapted to deliver the separated sheet to instrumentalities for operating upon said separated sheet at each rest period of said feeding means.

30 3. A sheet feeding apparatus, comprising in combination, a magazine for holding a plurality of sheets on edge in stack formation, separating devices for removing a single sheet from one side of said magazine, means for releasing said sheet to drop by gravity, means for feeding said separated sheet downwardly in a step by step movement, said feeding means being adapted to deliver the separated sheet to cutting instrumentalities for severing a strip from said sheet at each 35 rest period of said feeding means, and means for discharging the remainder of the sheet after the final strip is cut.

4. A sheet feeding apparatus, comprising in combination, a magazine for holding a plurality of sheets arranged on their edges in stack formation, 45 separating devices embodying a suction cup for removing rearwardly a single sheet from said magazine, means for releasing said sheet to drop edgewise by gravity, means for feeding said separated sheet in a step by step movement, and actuating devices associated with said feeding means and operating when said sheet has passed through a given step in its movement for bringing said suction cup into position for a subsequent sheet 50 separation.

55 5. A sheet feeding apparatus, comprising in combination, a magazine for holding a plurality of sheets in stack formation, separating devices embodying a suction cup for removing a single sheet from said magazine, means for releasing said sheet to drop edgewise by gravity, means for feeding said separated sheet in a step by step movement, actuating devices associated with said feeding means and operating when said sheet has 60 passed through a given step in its movement for bringing said suction cup into position for a subsequent sheet separation, and means for releasing each separated sheet from said suction cup when it is in position to begin its step by step 65 movement.

70 6. A sheet feeding apparatus, comprising the combination of a magazine for holding a plurality of sheets, an oscillating support mounted adjacent said magazine, suction cups carried by said support and adapted for engagement with a sheet 75

in said magazine for separating it from the other sheets, actuating devices comprising an oscillating arm operable adjacent said support, and clutch members for connecting said support with said oscillating arm to effect an oscillation of said support and its suction cups for the separation of a sheet from said magazine.

80

7. A sheet feeding apparatus, comprising the combination of a magazine for holding a plurality of sheets, an oscillating support mounted adjacent said magazine, suction cups carried by said support and adapted for engagement with a sheet in said magazine for separating it from the other sheets, actuating devices comprising an oscillating arm operable adjacent said support, clutch members for connecting said support with said oscillating arm to effect an oscillation of said support and its suction cups for the separation of a sheet from said magazine, and means for disconnecting said oscillating arm and support after said sheet has been separated.

85

8. A sheet feeding apparatus, comprising the combination of a magazine for holding a plurality of sheets, an oscillating support mounted adjacent said magazine, suction cups carried by said support and adapted for engagement with a sheet in said magazine for separating it from the other sheets, means for feeding said separated sheet in a step by step movement, actuating devices comprising an oscillating arm operable adjacent 105 said support, and in synchronism with said feeding means, clutch members for connecting said support with said oscillating arm, and controlling means operable at a predetermined step in said sheet feeding for bringing said clutch members into clutched relation for the separating and feeding of a subsequent sheet.

90

9. A sheet feeding apparatus, comprising a magazine for holding a plurality of sheets arranged on edge in stack formation, suction cups 115 for removing a single sheet from said magazine, cutting instrumentalities including a reciprocating slide for severing a sheet into strips, means for releasing said sheet to drop by gravity, means for feeding said separated sheet in a step by step 120 movement through said cutting instrumentalities, actuating devices connected with said slide, and means operating during one of the cutting strokes of said slide for connecting said suction cups with said actuating devices to effect the removal of 125 a subsequent sheet from said magazine.

110

10. A sheet feeding apparatus, comprising a magazine for holding a plurality of sheets resting on edge in stack formation, suction cups for removing a single sheet from said magazine, means 130 for feeding said removed sheet in a step by step movement in the direction of its gravity to operating instrumentalities including a reciprocating slide and actuating devices connected with said slide, means operating during one of the cutting strokes of said slide for connecting said suction cups with said actuating devices to effect the removal of a subsequent sheet from said magazine, and means for discharging the strips as cut from 135 said magazine.

140

11. A sheet feeding apparatus, comprising in combination, a magazine for holding a plurality of sheets on edge in stack formation, separating devices for removing a single sheet from one side 145 of said magazine, means for releasing said sheet to drop by gravity, and means for feeding said separated sheet downwardly in a step by step movement, said feeding means being adapted to deliver the separated sheet to instrumentalities 150

for operating upon said separated sheet at each rest period of said feeding means.

12. A sheet feeding apparatus, comprising in combination, a magazine for holding a plurality of sheets on edge in stack formation, separating devices for removing a single sheet from one side of said magazine, means for releasing said sheet to drop by gravity, means for feeding said separated sheet downwardly in a step by step movement, said feeding means being adapted to deliver the separated sheet to cutting instrumentalities for severing a strip from said sheet at each rest period of said feeding means, and means for discharging the remainder of the sheet after the final strip is cut.

13. A sheet feeding apparatus, comprising a magazine for holding a plurality of sheets arranged on edge in stack formation, suction cups for removing a single sheet from said magazine, means for releasing said sheet to drop by gravity, means for feeding said removed sheet to cutting instrumentalities including a reciprocating slide for severing a sheet into strips, means for feeding

said separated sheet in a step by step movement through said cutting instrumentalities, actuating devices connected with said slide, and means operating during one of the cutting strokes of said slide for connecting said suction cups with said actuating devices to effect the removal of a subsequent sheet from said magazine.

14. A sheet feeding apparatus, comprising a magazine for holding a plurality of sheets arranged on edge in stack formation, suction cups for removing a single sheet from said magazine, means for releasing said sheet to drop by gravity, means for feeding said removed sheet in a step by step movement to cutting instrumentalities including a reciprocating slide for severing a sheet into strips and including actuating devices connected with said slide, means operating during one of the cutting strokes of said slide for connecting said suction cups with said actuating devices to effect the removal of a subsequent sheet from said magazine, and means for discharging the strips as cut from said magazine.

ROBERT CURRIE.
